TIMING MECHANISM, PARTICULARLY FOR
WASHING OR DRY CLEANING MACHINES

William Jepson, London, England

Application November 28, 1931, Serial No. 577,812
In Great Britain December 1, 1930

2 Claims. (Cl. 161—1)

This invention relates to timing mechanisms for machines, particularly for washing or dry cleaning machines, of the type in which a series of operations is carried out in a predetermined order according to the setting of the machine.

In the timing mechanism according to the present invention, a supplementary control, hereafter referred to as the "position-control", is combined with the timing mechanism proper, hereafter referred to as the "time-control", so as to ensure that if, for some reason, the satisfactory performance or completion of any particular operation of the sequence is delayed the operation of the time control device will be temporarily suspended, until the said operation is completely performed, when the time-control is allowed to come into action again, the timing being automatically rendered subservient to the accurate performance of the several operations of the sequence.

The mechanism, object of this invention, is particularly adapted to the control of washing or dry cleaning and like machinery, the successful working of which depends on the successive operation of supply valves and drain valves, so as to accurately control the admission and draining of the various liquids (cold water, hot water, detergents and other washing reagents) in predetermined sequence and quantity, according to the laundering or other operation-sequence formula, in accordance with which it is desired that the machine should operate. It will be, however, readily understood that the mechanism can be used for controlling any predetermined sequence of operations of similar kind to that just described, namely, having for its object the displacement of any liquid or liquids, for any purpose to which the method of position-control herein described may be applied. Although the timing mechanism, object of the invention, is hereafter described in connection with the operation of a washing or dry-cleaning machine, its use is therefore not limited to the operation of such a machine, as will be made clear hereafter.

The principle and operation will be understood by reference to the drawing, in which Figure 1 is a side elevation of the present invention, and Fig. 2 is a vertical section taken substantially on the line 2—2 of Fig. 1.

In Figure 1, A is the time-control device proper, and B is the position-control. Reference character 1 is the record, here a perforated band, wound on the drum 2 pivoted at *a* and gradually fed on the drum 3, pivoted at *b*, by the action of the ratchet 4 and ratchet teeth 5 actuated by the

linkwork 6, 7, 8 pivoted at *b* and *c*. The element 8 carries a roller 9 which is normally depressed by a cam 10 integral with the rocking lever 11 actuated by the driving shaft of the machine the operation of which is to be controlled. The levers 6, 7, and 8 are returned to their normal position by gravity or by any other suitable means (not shown). At each reciprocation of the rocking lever, the cam 10 depresses the roller 12, thereby actuating levers 13, 14, 15 which are pivoted at 10 *d* and *e* which lowers the lever 15 carrying sleeve 16 inside of which slides the feeler 17, which is pressed against the record by the spring 18. Whenever the feeler 17 engages an unperforated portion of the record it merely slides in sleeve 15 16 against the pressure of the spring 18, which is adjustable by means of the screw 19. However when a perforation of the record advances beneath the feeler, the latter passes through the perforation in the record and strikes a projection 20 on a pawl 21 pivoted at 22 to the operating lever 23, thereby depressing the pawl 21 and causing the end 11*a* of the arm 11 to engage a notch 21*a* provided on the pawl 21. This pawl is provided with a two-position stop 21*b* pressed by 25 a spring 21*c* against a two-face abutting piece 23*a* carried by the operating lever 23, so that it remains indifferently in either the raised or the lowered position. On being engaged by the rocking lever 11, the pawl 21 moves forward, and 30 causes the lever 23 to rock forward, actuating the particular part of the machine desired to be operated by means of the rod or Bowden wire 25, secured to it at 26, and, at the same time, pushing the roller 9 by means of its cam-like projection 27, causing the ratchet to advance by several teeth, thereby feeding the record forward so as to bring the perforation beyond the line of action of the feeler 17. As it reaches its forward position, the pawl 21 first depresses the roller 28 40 of the catch 29 pivoted at *f*, against the action of a spring 29' by means of an incline 21*d* provided at the end of the pawl, the roller 28 being lifted by the spring as soon as it is released by this incline and engaging the notch 21*e* in the 45 pawl, thereby locking it, and with its lever 23, which therefore remains in the operative position, at the same time maintaining the roller 9 out of the range of action of cam 10 of the rocking lever 11, so that the feed of the record ceases. 50 The catch 29 is capable of being depressed by a feeler 11*b* carried by the rocking arm 11, which feeler, at each forward movement of the arm 11 strikes against the surface of a hollow drum 30, pivoted at *g*, and, normally, is caused to slide 55

back into its housing in the arm 11 against the pressure of the spring 11c but, when a perforation 31 on the drum happens to coincide with its line of action, the feeler 11b penetrates in the 5 aperture of the drum and reaches a projection 32 carried by the catch 29, depressing the latter and causing it to release the pawl 21, thereby allowing the operating lever 23 to return to the inoperative position under the action of a return spring 28. The drum 30 is mounted on a sheave 33 actuated by a float by means of the cord 34. After the termination of the sequence of operation, the record is re-wound on the drum 2 by means of the handle 2a. In the operation, for 10 example, of a water tap, the rocking of the arm 11 feeds the record forward until the first perforation passes under the feeler 11, when the lever 23 is pushed forward, as described, and the tap is opened by the rod or wire 25, and 15 maintained in the open position owing to the fact that the lever 23 is locked in its forward position, so that water is entering the container the level of liquid in which it is required to control. As the water rises in the container, the 20 float rises and the drum 33 revolves, and with it the drum 30. While this takes place, the feeler 11b inoperatively strikes the surface of the drum 30, but as soon as the aperture 31 comes in the proper position, which is to the right of the 25 position shown in the drawing and substantially over the projection 32, and which position is adjusted to correspond to the correct level of the water in the container, the feeler penetrates into the drum 30 and releases the lever 23, which, 30 rocking back, either positively closes the tap or allows it to close under the action of a weight or suitable mechanism, at the same time allowing the feeding ratchet 4 to resume its feed action.

It will be understood that the means described

herein to actuate the portion of the mechanism concerned with the position-control (namely, a float, the position of which is governed by the level of the liquid the displacement of which is required) is by no means a characteristic of the timing mechanism according to this invention, and that it may be replaced by any other means depending on the movement or position of any member of the actuated mechanism, so that the timing mechanism, object of this invention, can be applied generally to the control of a predetermined sequence of operations of any description capable of supplementary position-control by means actuated by a material element variable in position, without departing from the spirit of the invention as described above. It is, for example, particularly suitable for automatically stopping and restarting machines, for operating a dumping apparatus and like applications.

Having now particularly described my invention 20 what I claim as new and desire to protect by Letters Patent is:—

1. A timing mechanism for controlling a series of predetermined operations to be performed by a machine comprising, a perforated member, a drive shaft, a rocking lever actuated by said shaft, an operating lever, means actuated by said rocking lever to advance said perforated member, a pawl pivotally connected to said operating lever, means controlled by said perforated member adapted to actuate said pawl into locking engagement with said rocking lever and means carried by said operating lever to affect operation of a particular part of the machine desired.

2. A device according to claim 1 including means adapted to return said operating lever to its original position.

WILLIAM JEPSON.
